United States Patent Office

Des. 233,851
Patented Dec. 3, 1974

233,851

WATCH FACE

Alex Luna Miramon, 9465 Wilshire Blvd.,
Beverly Hills, Calif. 90212

Filed Apr. 5, 1973, Ser. No. 348,335

Term of patent 14 years

Int. Cl. D10—07

U.S. Cl. D10—123

The figure is a top plan view of a watch face showing my new design, the rear being plain and unornamented.

The watch face is conventionally of no appreciable thickness.

I claim:

The ornamental design for a watch face, as shown and described.
